FINGER COT

George L. Gross, Hartford, Conn.

Application July 24, 1946, Serial No. 685,971

2 Claims. (Cl. 2-21)

1

This invention relates to finger cots or stalls and the method of making the same.

An object of the invention is to provide a tubular sheath of a novel construction and of a suitable material which serves as a protective guard on the fingers of the hand.

A further object of the invention is to provide a finger cot of novel construction which affords protection to the fingers of the operator of buffing and grinding wheels or the like.

Another object of the invention is to provide a seamless finger cot or stall which is substantially non-fraying in character and which gives protection to the operator of various types of machines.

A still further object is to provide a method of making finger cots having smooth and seamless surfaces exposed to machine shop tools and machines.

Other objects of the invention will be apparent from the following description and accompanying drawing in which:

Figure 1 is a perspective view of a section of knitted tubing before being converted to a finger cot;

Figure 2 is a perspective view, partly in section, of the apparatus used to make the finger cot embodying the present invention; and

Figure 3 is a perspective view, partly in section, of a finished finger cot embodying the present invention.

The present invention is concerned with the protection of the fingers and hands of workers engaged in buffing, polishing, grinding, sanding, burring, soldering, cable forming, armature winding, blanking, stamping, operating punch presses, and handling rough sharp articles. Machines having rapidly revolving wheels present serious accident hazards to the fingers and hands which hold tools or objects to be worked, buffed or polished adjacent said wheels. It has been found that the wearing of a protective glove encompassing all the fingers of the hand subjects the operator of a buffing wheel, for example, to the hazards of having the whole hand and arm injured when one small part of the glove becomes frayed. A frayed edge or loose strand of thread is readily caught by the periphery of the buffing wheel and practically instantaneously pulls the gloved hand toward the rapidly revolving wheel, thereby causing serious accidents.

This hazard has been obviated to some limited extent in the past by replacing the integral glove with several separate stalls or cots that are placed upon each finger. Unfortunately, however, these

2

finger cots have had a selvage or binding of cotton thread or the like which when rubbed by the buffing wheel broke and raveled thus exposing the coarse edge of the material of the cot and causing it to fray and spread out. Both the loose broken thread of the selvage and the resultant frayed end of the cot presented a serious accident hazard to the operator. Since the selvaging was the weakest part of the cot it quickly broke and the rapid wearing and fraying of the cot material was accelerated, thus requiring frequent and expensive replacements.

I have discovered that the danger of broken selvage and resultant fraying can be obviated by 15 my novel invention which eliminates the selvage from the operating end of the finger cot which is nearest the buffing wheel and which is subject to greatest wear. I provide a new finger cot of a novel double ply structure which presents a 20 smooth and seamless knitted end and side surfaces to the buffing wheel. This novel construction substantially eliminates the accidents which have occurred to operators of buffing wheels and the like using the conventional finger cots. The 25 improved method of the present invention also facilitates the manufacture of finger cots having smooth and seamless surfaces and ends exposed to the rapidly revolving buffing and grinding wheels and machine parts.

30 Referring now to the drawing, Figure 1 shows a seamless open-ended tube 11 which is preferably tightly knitted of selected hard twisted cotton yarn. Being made of knitted material tube 11 is elastic and self-conforming.

35 Figure 2, partly broken away for the purpose of clarity, shows the preferred method I employ in converting the flexible knitted fabric tube into a finger cot embodying the present invention. The tube 11 is drawn about half of its length over 40 metal cylinder 21 fixed firmly on base 22. The remaining part of the knitted tube 11 is then pushed into the interior of said cylinder in such a manner that said tube is stretched for half its length 25 outside the cylinder while the other 45 half 26 is inside the cylinder. The folded tube 11 is then removed from the cylinder in such a manner that the two sections 25 and 26 of tube 11 are maintained in the same retroverted position relative to each other. An alternative method of 50 making the cot would be first to insert the tube 11 half of its length 26 into the cylinder and retrovert or turn the remaining half 25 back over itself and over the outside of the cylinder.

Figure 3 shows a finished finger cot 31 embodying the present invention placed in position upon

a finger 24 of the hand. As can be seen from the broken away section of Figure 3, the finger cot is an open ended fabric body having two concentrically disposed tubular plies, the outer ply 35 being an integral extension of the inner ply 36. The said plies 35 and 36 are so arranged that one surface of the tubular fabric body is disposed on the outside of the inner ply and the inside of the outer ply, and the other surface of the tubular fabric body is disposed on the inside of the inner ply and the outside of the outer ply. This feature of construction makes possible the manufacture of a tubular fabric body having seamless continuity from the inside surface to the outside surface. The finger cot or stall is positioned upon the finger in such a manner that the seamless open end 33 is nearest the finger tip 34. The other open end of the cot which originally started as the open ends of tube 11 in Figure 1 is provided with stitching 32. I have found that in practice the parts of the finger cots that are exposed to the hazards of buffing wheels and the like are the ends at the finger tips and sides. The stitched end 32 of the finger cot at the crotch apex between the fingers is rarely touched by the buffing wheel.

Being seamless both on the operative end and on the sides, the fingers cots or stalls of my invention have a greatly longer life than cots used heretofore because there are no seams or selvages which are liable to be caught, frayed, broken or gripped by rapidly rotating buffing or grinding wheels and the like. The improved structure of my finger cots also provides vastly greater protection to shop workers and has practically eliminated accident hazards which have been due in the past to faultily constructed and poorly designed finger protective devices. In the finger cots of the present invention the seamless two-ply construction provides for self-conforming flexibility and non-spreading open ends which prevents the operative part near the finger-tip from spreading out even after considerable wear. Conventional finger cots with seamed or selvaged ends and sides have spread substantially with a small amount of wear and have not only interfered with fine buffing and shop work operations but also have caused numerous accidents. On the other hand, my present finger cots of double-ply seamless construction have greatly increased production and shop efficiency wherever used and because of their superiority have increased workers'

confidence on approaching hazardous buffing and machine shop jobs.

Although Figure 3 shows only one finger cot placed upon a finger of the hand for purposes of clarity of illustration, it is to be understood that finger cots may also be placed upon all the fingers and thumb of either hand or both depending upon the particular buffing or machine shop operation that is being performed. The present finger cots 10 may be fabricated and constructed in various lengths and diameters to conform to the sizes of thumbs and fingers. While the preferred embodiment of the present invention has been described as comprising a fabric of hard twisted cotton 15 yarn, it is intended that any suitable fabric may be used such as wool, nylon, hemp, linen and the like.

While the present invention, as to its objects and advantages, has been described herein as 20 carried out in specific embodiments thereof, it is not desired to be limited thereby but it is intended to cover the invention broadly within the spirit and scope of the appended claims.

What is claimed is:

- 25 1. An open ended tubular finger cot having a seamless double ply open end and double ply seamless sides, said double ply open end being characterized by resistance to fraying and raveling when rubbed and abraded in grinding, buffing and polishing operations.
- 30 2. A finger cot produced from a seamless open ended fabric tube which is turned back upon itself to provide a protective covering having a seamless and unselvaged double ply open end 35 seamless double ply sides, said double ply open end being characterized by resistance to fraying and raveling when rubbed and abraded in grinding, buffing and polishing operations.
